TIME SWITCH

Carl E. Sundberg, Quincy, Mass., assignor to
 Albert & J. M. Anderson Manufacturing Company,
 Boston, Mass., a corporation of Massachusetts

Application December 20, 1930, Serial No. 503,797

11 Claims. (Cl. 185—40)

This invention relates to a time switch and is herein shown as embodied in a time switch of the type illustrated and described in United States Patent No. 779,249 dated January 3, 1905.

5 One object of the invention is to provide a novel and improved construction of time switch of the character specified in which provision is made for controlling the operation of the switch to prevent its being opened or closed when the spring motor 10 of the switch operating mechanism has been unwound to a predetermined extent.

A further and more specific object of the invention is to provide a novel and improved construction of time switch having a stop mechanism 15 for controlling the operation of the switch member when the spring motor has been unwound to a predetermined extent, and in which provision is made for facilitating the variation in the number of operations of the time switch before the stop mechanism becomes effective.

With these objects in view and such others as may hereinafter appear, the invention consists in a time switch provided with a stop mechanism substantially as hereinafter described and particularly defined in the claims at the end of this specification.

In the drawings illustrating a preferred embodiment of the invention—

30 Fig. 1 is a front elevation of a time switch with the outer portion of the usual casing removed;

Fig. 2, a rear elevation of the switch-operating mechanism, stop mechanism and associated parts in one position of operation;

35 Fig. 3, a similar view with the parts in a different position of operation, as will be described,

Fig. 4, a detail in section on the line 4—4, Fig. 3.

Figs. 5 and 6, detail views to illustrate the engagement of the arms 14, 15 with the time dial;

40 Fig. 7, a side elevation of the disk 57 and the switch-operating rod 40;

Fig. 8, a plan of Fig. 7, and

Fig. 9, a detail in section to illustrate the sleeves carrying the tripping dogs or cams.

45 In general time switches of the character illustrated and described in the above-mentioned Patent No. 779,249 of January 3, 1905, comprise one or more switch members arranged to be operated to open and close a circuit intermittently by switch-operating mechanism including a spring motor. The switch-operating mechanism is controlled in its operation by a clock mechanism so that in the operation of the time switch, the switch members are periodically opened and 55 closed.

In accordance with the present invention provision is made for controlling the operation of the switch-operating mechanism when the spring motor has become unwound to a predetermined extent, to the end that the switch may not reach

a condition where the spring motor becomes too weak for effecting proper operation of the switch with the accompanying liability of the switch being burnt out.

For this purpose the time switch is provided 5 with a stop mechanism, preferably arranged to permit convenient alteration of the ratio of co-operating gears forming a part thereof, so as to permit variation of the period of time which may elapse before the stop mechanism becomes 10 operative, and to thereby render the time switch easily adapted to different conditions of use.

In some instances it is desirable that the time switch be designed so as to require rewinding every eight days, while in other instances it may 15 be desirable that a period of nine or ten days elapse before rewinding is necessary, and the construction of the present switch is preferably such as to enable convenient alteration of co-operating gears in the stop mechanism for permitting this 20 result to be accomplished.

Referring now to the drawings which illustrate the preferred embodiment of the invention, the time switch may and preferably will except as to details to be hereinafter pointed out, comprise 25 the time switch illustrated in the Patent No. 779,249 above referred to, and in general such time switch comprises a clock mechanism 12 and a switch-actuating mechanism 13 whose operation is controlled by the hands 14, 15 of a time 30 dial 16 geared to the clock mechanism and to the switch-actuating mechanism as illustrated in Fig. 1. The clock mechanism 12 is provided with the usual gear 17 which meshes with a gear 18 35 formed on the periphery of the time dial 16 mounted upon a supporting shaft 19. The time dial 16 is provided with radial slots 20 into which bent ends or fingers formed on the extremity of the arms 14, 15 may be extended to effect rotation 40 of the said arms with the time dial 16. The arms 14, 15 are loosely mounted upon the shaft 19, being mounted upon the ends of sleeves 22, 23 rotatably mounted with relation to each other and upon the supporting shaft 19. The sleeves 45 22, 23 carry tripping cams or dogs 24, 25, and provision is made, as will be described, for controlling the operation of the switch-actuating mechanism by the tripping cams 24, 25.

As illustrated in Fig. 1, the switch comprises 50 two switch units 28 of standard construction having the usual switch brushes 34 which are adapted in the closed position of the switch to make contact with fixed terminals 35, thus closing the circuit controlled by the time switch. Each movable member or switch unit 28 is mounted upon a lever 36 pivoted at 37 upon a stationary bracket 38.

Provision is made for moving the switch arms 36 to swing the switch members 28 into a position 60

to close the circuit at the contacts 35 and also to withdraw the switch members 28 from such position into an open position such as is illustrated in Fig. 1; and as herein shown see Figs. 1 5 and 7 a bar or rod 40 is provided forming a connection between the switch-actuating mechanism 13 and the switches, and which is raised and lowered by the switch-actuating mechanism when the tripping dogs 24, 25 are moved into a definite 10 position at each revolution of the time dial.

The connecting rod 40 is pivotally connected to toggle levers 42 and the center pivot 43 is arranged to engage and be guided in its movements in a slot 44 in the connecting rod 40.

15 Referring now to Figs. 2, 3 and 9 the switch-operating mechanism herein shown includes the tripping cams or dogs 24, 25 whose relative position may be adjusted by means of the hands 14, 15 of the time dial to which the tripping dogs are 20 respectively connected to move therewith and with relation to each other, so that at each cycle or revolution of the time dial the tripping cams or dogs 24, 25 will each be brought into contact with a finger 44 on an escapement lever 45 pivotally 25 mounted upon a fixed shaft 46. The escapement member 45 is normally urged into a position in which the finger 44 is positioned in the path of the approaching tripping cams 24, 25 by a spring 47 attached to a fixed pin 48 on the frame, and 30 to a pin 49 on the escapement lever 45.

The escapement lever is also provided with a finger 50 which is arranged to be engaged by the end of a detent lever 51 mounted upon a shaft 52 and retained upon the shaft by a cotter pin 53 as 35 shown.

40 The detent lever 51 is yieldingly urged by a spring-pressed plunger 54 against a lug 55 comprising one of two weighted lugs 55, 56 forming part of a disk 57 see Figs. 2, 3, 7 and 8 fixed upon the shaft 52 to rotate therewith. The shaft 52 is 45 rotatably mounted in the supporting frame for the operating mechanism and is driven through suitable gears 158, 159 by the spring motor 31, the gears 158, 159 being conventionally indicated in Figs. 2 and 3.

From the description thus far it will be observed that when the escapement lever 45 is swung to the left (viewing Fig. 2) by either of the tripping cams 24, 25, the finger 50 will be removed from 50 the path of one end of the detent lever 51, thus permitting the spring motor 31 to effect through the driving shaft 52 the rotation of the weighted disk 57 in the direction of the arrow, and after the end of the detent lever 51 has passed the finger 50 it is engaged with a second finger 58 and then released therefrom by the spring 47 which returns the escapement lever into its normal position and brings the finger 50 into the path of the other end of the detent lever 51 to hold it from 55 turning until again released by one of the tripping dogs 24, 25.

The rotation of the disk 57 is arrested by the engagement of the second end of the detent lever 51 with the finger 50 after the disk 57 has made 60 one-half a revolution.

The described half-revolutions of the disk 57 are utilized in accomplishing the periodic opening and closing movements of the switch members 28 as above described, and to this end the disk 57 is 65 provided with a stud 60 upon which the upper end of the connecting rod or arm 40 is hung see Figs. 2 and 7 so that upon one-half of each revolution of the disk 57 downward motion is imparted to the connecting rod 40 to effect a closing 70 of the switch members 28, and upon the next half

revolution of the disk 57 the rod 40 is lifted again, thus opening the switch members.

In order to control the operation of the switch-actuating mechanism when the spring motor 31 has become unwound to a predetermined extent, 5 the weighted disk 57 is provided with a stop lug or member 70, which is arranged to co-operate with another stop lug or member 72 carried by an arm or lever 74 pivotally mounted upon the shaft 76 of the spring motor 31 and arranged as will be 10 described to be moved into a position to engage the stop member 70 when the arm 74 is raised or moved from the position shown in Fig. 2 into that shown in Fig. 3. The arm 74 is normally urged by a spring 85 having one end connected to a 15 pin 83 on the arm 74 and its other end to a fixed pin 84, into a position such as is shown in Fig. 2, in which the stop member 72 is withdrawn from the path of movement of the stop member 70, and in this position the stop member 72 has no effect 20 upon the normal revolution of the disk 57 by the spring motor 31 during the opening and closing of the switch members 28 as above described.

Provision is made for effecting the raising of the arm 74 by the spring motor 31 to bring the 25 stop member 72 into the path of movement of the stop member 70, to thereby prevent further rotation of the disk 57, and as herein shown such movement is imparted to the arm 74 by a pin 90 on the inner side of a gear 82 loosely mounted on 30 a stud shaft 83. The pin 90 is arranged to engage a cam surface 94 on the underside of the arm 74 during the rotation of the gear 82 in the direction of the arrow 95 shown in Fig. 2. The gear 82 is arranged to mesh with a pinion 96 35 mounted upon the shaft 76 to rotate therewith. The shaft 76 constitutes the winding shaft to which one end of the spring motor 31 is attached, the other end of the spring being attached to the barrel of the spring motor as is the usual practice. 40

During the normal operation of the time switch, the shaft 76 is intermittently rotated by the spring motor 31 in a direction such as to cause the gear 82 and the cam pin 90 to move in the direction of the arrow 95 shown in Fig. 2, from 45 the position shown therein until the cam pin 90 engages the cam surface 94 on the under side of the arm 74 and operates to raise the arm 74 and to move the stop lug 72 carried thereby into the path of the lug 70 upon the disk 57, thus preventing 50 further movement of the disk 57 and further operation of the time switch. It will thus be seen that when the spring motor 31 is released by the tripping dogs 24, 25, the spring motor 31 is 55 unwound at its outer and inner ends, the outer end effecting rotation of the disk 57 and its attached stop member 70, and the inner end of the spring motor 31 effecting rotation of the shaft 76 and through the pinion 96 and gear 82 and pin 90 effecting movement of the second 60 stop member 72 toward and into the path of the rotatable stop member 70. The lugs 70, 72 are arranged so that when engaged, the switch members 28 will be in their extreme open position, thus preventing the operation of the switch 65 members 28 by the spring motor 31 when the latter is in a predetermined weakened condition and such as to be unable to move the switch members into their fully opened position, whereby any tendency or liability of arcing to occur between the brushes 34 and the contact members or terminals 35 and the maintenance of such an arc with the switch members 28 in an intermediate position, with liability of the switch being 70 burnt out is avoided.

When the spring motor 31 is to be rewound, the shaft 76 is turned by hand with the usual key, causing reverse movement of the gear 82 from the position shown in Fig. 3 to that shown in Fig. 5, 2, and in order that the gear 82 may be re- 5 volved in such reverse direction indicated by the arrow 97 only until the cam pin 90 has been brought to a position such as is shown in Fig. 2, which may be considered its starting position, 10 while permitting the spring motor 31 to be fur- 15 ther wound up, if desired, the gear 82 is prefer- 20 ably mutilated to provide a blank space 98 ar- 25 ranged with respect to the position of the cam pin 99 on the gear 82, so that when the parts are in 30 the position shown in Fig. 2 the pinion 96 may 35 revolve idly in the blank 98 on further winding- 40 up of the spring motor 31 without effecting fur- 45 ther revolution of the gear 82 in a reverse direc- 50 tion. This permits the spring motor 31 to be 55 completely wound, and after the spring motor has 60 become wound and the switch resumes its normal 65 operation, the pinion 96 again picks up the teeth 70 on the gear 82 and effects revolution of the gear 75 82 again in the direction of the arrow 95, shown 80 in Fig. 2.

As illustrated in Figs. 3 and 4, the pinion 96 is provided with a square bore and fitted onto the squared end of the shaft 76 to rotate therewith. The pinion 96 is provided with an elongated 30 hub 100 upon which the hub 102 of the arm 74 is loosely mounted, and a retaining collar 103 is secured to the hub of the pinion 96 so that the pinion 96, arm 74 and collar 103 constitute a removable unit which is normally retained in operative position upon the end of the square shaft 76 by the gear 82 behind which the arm 74 is arranged to extend, as illustrated in Figs. 2 and 3.

The gear 82 is herein shown as removably retained upon the shaft 83 by a cotter pin so that 40 by removing the cotter pin and slipping off the gear 82 on the end of the shaft 83, the pinion 96, arm 74 and collar 103 may then be removed.

From the description thus far, and by reference to Figs. 2 and 3, it will be observed that the 45 number of times that the switch may operate on one winding of the spring motor is determined by the ratio of the gear 82 to the pinion 96; the larger the ratio, the greater the number of times it is possible for the switch to operate, and vice 50 versa. It may be desirable that this ratio be varied according to the particular conditions of use to which the time switch is to be put, and in accordance with the present invention different sets of gears and pinions may be employed for 55 accomplishing this purpose, and the present construction is such as to facilitate the substitution of different sets of the gear and pinion and without disturbing the standard construction of the remaining portions of the time switch.

As above described it is merely necessary to 60 remove the cotter pin from the shaft 83 in order to enable both the gear 82 and the pinion 96, together with the arm 74, to be removed, so that the substitution of a new set of parts may be ac- 65 complished in a minimum time and at a minimum expense and without detracting from the oper- 70 ativeness of the remaining portions of the time switch.

In this manner it is possible to regulate the 75 period within which the time switch may be operated before the stop mechanism becomes effective to adapt the time switch to different conditions of use.

In some instances it may be desirable to effect 75 the opening or closing of the switch by a manual-

ly-operated tripping device, and as herein shown such a tripping device comprises the release arm 104 secured to a shaft 105 and connected with a lever 106 mounted on said shaft at the front of the casing, as shown in Fig. 1. The lever 106 is held in a normal position by a spring 107, and when the lever is thrown downward, the release arm 104 may be brought into contact with the finger 58 and manually trip the escapement lever 45 out of the path of the detent lever 51 and thus effect a manual tripping of the time switch. 10

It will be observed that the spring motor may be further manually wound after the pinion 96 ceases to rotate the gear 82, and as a result, it is assured that the spring motor 31 will be provided 15 with sufficient power to move the switch member 28 into its fully opened position at the time the stop member 72 is brought into the path of the stop member 70 to arrest rotation of the disk 57 by the spring motor. 20

When the stop members 70, 72 are in their operative relation shown in Fig. 3, the spring motor 31 is capable of having its inner end rewound by the operator turning the shaft 76 so as to turn the gear 82 in the direction of the arrow 95 25 in Fig. 2 and if the gear 82 were not mutilated, the gear 82 would be continuously rotated until the spring motor was wound up to its initial condition. 25

During this rewinding of the spring motor, the 30 lever or arm 74 would be oscillated toward and from the path of the rotatable stop member 72, until the operator ceased to turn the shaft 76.

Such continuous oscillation of the lever 74 may be avoided as herein shown by mutilating the 35 gear 82 and providing it with the blank space 98, which is arranged to register with the pinion 96 at or about the time the pin 90 has passed beyond the high point of the cam 94 and into the position represented in Fig. 2. 40

Rotation of the shaft 76 can then be continued by the operator without rotating the gear 82, and the spring motor is further rewound at its inner end until it has been wound sufficiently to ensure proper operation of the switch by the unwinding 45 of the outer end of the spring motor. It will thus be seen that one end of the spring motor is employed to operate the rotatable stop member 70, and the other end of the spring motor is employed to operate the oscillating stop member 72, and 50 that the spring motor is rewound at the end which oscillates the second stop member. 50

While the preferred embodiment of the invention has been herein illustrated and described, it will be understood that the invention may be 55 embodied in other forms within the scope of the following claims.

Having thus described the invention, what is claimed is:—

1. In a time switch, in combination, a spring 60 motor, a rotatable member connected therewith to be operated thereby, and stop mechanism including a stop member carried by said rotatable member and rotated by the unwinding of said spring motor, a co-operating stop member also 65 operated by the spring motor to be movable by the unwinding of the spring motor into the path of the first-mentioned stop member and means for moving the cooperating stop member out of the path of the stop member carried by said ro- 70 tatable device. 70

2. In a time switch, in combination, a spring 75 motor, a switch-operating member connected therewith to be operated thereby, and a stop mechanism for controlling the operation of the 75

switch-operating member comprising a removable pinion driven by the spring motor, a removable gear meshing therewith and provided with a cam member, and a movable stop member adapted to be moved by the cam member when the gear has revolved a predetermined amount to move the stop member into operative position, said gear being mutilated to enable the spring motor to be wound without effecting movement of the gear after the same has been returned to its initial operating position.

3. In a time switch, in combination, a movable switch member, a spring motor for moving it, and a stop mechanism for controlling the operation of said switch member by said spring motor, said stop mechanism having a member movable by the unwinding of said spring motor and a co-operating member movable toward the path of movement of the first-mentioned stop member by said spring motor when the latter is unwound at each operation of the switch member by said spring motor to render the spring motor inactive to operate said switch member when said spring motor has been unwound a predetermined amount less than its full amount.

4. In a time switch, in combination, a movable switch member, a spring motor for moving it, and a stop mechanism for controlling the operation of said switch member by said spring motor, said stop mechanism having a member movable by the spring motor and a cooperating member movable into its inoperative position when the spring motor is rewound and movable toward the path of movement of the first-mentioned stop member by said spring motor when the latter is unwound at each operation of the switch member by said spring motor, and means for enabling the winding-up of the spring motor to be continued without influencing the second stop member after the latter is in its inoperative position.

5. The combination with a spring motor, of a rotatable device driven by said spring motor, a switch member connected with said rotatable device to be operated thereby, a stop member carried by said rotatable device, a cam lever movable with relation to said rotatable device, a stop member carried by said cam lever, a gear rotated by the unwinding of said spring motor and a device carried by said gear and co-operating with said cam lever to move its stop member into position to be engaged by the stop member on the rotatable device and arrest rotation of the latter before the spring motor has been weakened to such extent as to be unable to move the switch member into its fully opened position.

6. The combination with a spring motor, of a rotatable device driven by said spring motor, a stop member carried by said rotatable device, a cam lever movable with relation to said rotatable device, a stop member carried by said cam lever, a gear rotated by the unwinding of said spring motor and a device carried by said gear and co-operating with said cam lever to move its stop member into position to be engaged by the stop member on the rotatable device and arrest rotation of the latter before the spring motor has been weakened to such extent as to be unable to move the switch member into its fully opened position.

7. The combination with a spring motor, of a rotatable device driven by said spring motor, and a stop mechanism for said rotatable device com-

prising a member carried by said rotatable device, a cam lever, a stop member carried by said lever, a mutilated gear driven by the unwinding of said spring motor and provided with means for moving said cam lever with relation to said rotatable device to bring the stop member on said cam lever into operative relation to the stop member on said rotatable device before the spring motor has been weakened to such extent as to be unable to move the switch member into its fully opened position.

8. In a time switch, in combination, a rotatable shaft, a spring motor having an end connected with said shaft to rotate the latter by the unwinding of the spring motor, a rotatable stop member, gearing connecting said rotatable stop member with said spring motor to enable said stop member to be rotated by said spring motor a plurality of times in the same direction when the latter is unwinding, a second stop member movable into and out of the path of the rotatable stop member, and gearing actuated by said rotatable shaft and operatively connected with said second stop member to effect movement of said second stop member into the path of the rotatable stop member by the unwinding of said spring motor.

9. In a time switch, in combination, a rotatable shaft, a spring motor having an end connected with said shaft to rotate the latter by the unwinding of the spring motor, a rotatable stop member, gearing connecting said rotatable stop member with said spring motor to enable said stop member to be rotated by said spring motor a plurality of revolutions in the same direction when the latter is unwinding, a second stop member movable into and out of the path of the rotatable stop member, and gearing actuated by said rotatable shaft and operatively connected with said second stop member to effect movement of said second stop member into the path of the rotatable stop member by the unwinding of said spring motor.

10. In a time switch, in combination, a rotatable stop member, a second stop member movable into and out of the path of the rotatable stop member to arrest and permit rotation of the latter, and a spring motor operatively connected with both of said stop members to effect rotary movement of the rotatable stop member a plurality of revolutions in the same direction and movement of the second stop member into the path of the rotatable stop member by the unwinding of the spring motor.

11. In a time switch, in combination, a spring motor, a device rotatable a plurality of revolutions in the same direction by the unwinding of said spring motor, a stop member movable with said rotatable device, a second stop member movable by the unwinding of said spring motor into the path of the first mentioned stop member to arrest rotation of the first mentioned stop member when the spring motor has been unwound a predetermined amount.

CARL E. SUNDBERG.
